UNITED STATES PATENT OFFICE.

JOHN A. PILCHER, OF ROANOKE, VIRGINIA.

DRIFTING ATTACHMENT FOR LOCOMOTIVES.

1,132,030.

Specification of Letters Patent. Patented Mar. 16, 1915.

Application filed June 6, 1914. Serial No. 843,472.

To all whom it may concern:

Be it known that I, JOHN A. PILCHER, a citizen of the United States, residing at Roanoke, in the county of Roanoke and State of Virginia, have invented certain new and useful improvements in Drifting Attachments for Locomotives, of which the following is a specification.

The principal object of this invention is to provide means for admitting steam to the cylinders of locomotives when the main throttle valve is closed, particularly when the locomotive is drifting.

With the use of superheated steam the cylinders of locomotives become highly heated and when the locomotive is drifting with the throttle valve closed and all steam shut off from the cylinders although the lubricating oil continues to flow into the cylinders, yet the absence of the necessary atomizing steam causes very imperfect lubrication. The friction of the reciprocating parts may thus even increase this temperature of the cylinder walls and the piston.

At the same time the vacuum relief valves are admitting air to the cylinders, and at this high temperature the air combines with the free oil to carbonize it and it is deposited on the cylinder walls where it is disastrous to all of the wearing parts. With the admission of a small supply of preferably saturated steam to the cylinders when the locomotive is drifting, continuous lubrication is effected. In some instances this steam has been supplied by an auxiliary pipe by-passed around the throttle valve with a simple hand-operated valve in this pipe within reach of the engineer. Various devices have also been tried out which attempt to make this an entirely automatic operation.

Neither of these methods has proven successful, however; the first for the reasons that the engineer often fails to open the valve in the auxiliary steam line when on a comparatively short drift, thereby losing much of the value of the device, and frequently after having opened this valve he will forget to close it. When the throttle is then closed and the locomotive brought to a stand the forgotten supply of steam to the cylinders will gradually build up pressure with the result that the locomotive will creep. This creeping is very liable to cause serious accident accompanied by personal injury. Entirely automatic devices are like-

wise not a success because of the liability of failure of operation.

Further objects of this invention, therefore, are to provide a device which entirely obliterates the possibility of the locomotive creeping and at the same time insures that drifting steam will be supplied to the cylinders on every occasion when the throttle is closed.

With the hereinbefore described objects and others in view my invention consists in the construction, combination and arrangement of parts as will be herein described and finally claimed.

In the drawings Figure 1 is a side elevation of a locomotive having my invention applied thereto, various parts being shown broken or removed for simplicity. Fig. 2 is a perspective view of a portion of the rear end of the locomotive showing a portion of my invention in its relation to the throttle operating lever. In this figure the throttle operating lever is shown in full lines in the closed position and in dotted lines in the open position. Fig. 3 is a longitudinal sectional elevation of the auxiliary steam control valve and Figs. 4 and 5 are broken perspective views of the rotary piston valves contained within this steam control valve. Figs. 6, 7 and 8 are transverse sections of the steam control valve taken on the line DE, Fig. 3 and seen in the direction of the arrow F. These figures are drawn to show various positions of the parts of this valve, one valve arm being drawn in skeleton lines although it is not in reality within the scope of the sections. Figs. 9 and 10 are transverse vertical sections of the by-pass valve, these two figures being given to show different positions of the parts of this valve.

Referring to the drawings in which like parts are given the same reference numbers wherever they occur, 1 represents a locomotive having a steam dome 2, throttle 3, dry pipe 4, cylinders 5, and cylinder steam pipes 6. These parts are of the customary construction, the dry pipe 4 leading at the front end to the steam pipes 6. In the drawings this connection is not shown, it being omitted because of the multiplicity of parts in the smoke box. Also, but one of the cylinders 5 and the steam pipes 6 are shown, it being understood that a duplicate arrangement of cylinder and steam pipe occurs on the opposite side of the locomotive.

From the dome 2 or some other convenient source of steam I lead a pipe 7 which is adapted to convey steam from the boiler to a steam control valve 8. From the control valve 8 a steam pipe 9 passes to a by-pass valve 10, and steam pipes 11 and 12 lead from this by-pass valve 10 to the cylinder steam pipes 6 and the exhaust pipe 13 respectively, the pipe 11 having two branches 11^a and 11^b, one leading to each of the two cylinder steam pipes. These pipes and fittings thus constitute an auxiliary steam line adapted to convey steam from the boiler to the cylinders around the throttle valve.

The control valve 8 is so constructed and is so connected with the throttle operating lever 14 that when the throttle operating lever is moved to the open position the control valve 8 will shut off steam from the pipe 9 and when the throttle operating lever is in the closed position and the control valve is admitting steam to the pipe 9 said control valve may be manually closed, independently of the throttle operating lever, to shut off steam from the pipe 9. The details of this control valve might be arranged in various ways, the valve in its present form consisting of a body 15 having connections at 16 and 17 for the attachment of the pipes 7 and 9 respectively. Within the body 15 are cylindrical valve chambers 18 and 19 and rotatably fitted in these chambers are cylindrical valves 20 and 21 respectively. These valves 20 and 21 are of the piston type at the ends, having packing rings 22 to prevent the endwise movement of the steam. The central portion, however, is of the customary rotary valve construction, a portion of the periphery being cut away at 23 and 24 to form a steam passage and a portion remaining at 25 and 26 to form a port closure or bridge.

Integral with or secured to the outer ends of valves 20 and 21 are stems 27 and 28 respectively and these stems pass through suitable stuffing boxes 29 and 30.

Secured to the outer end of valve stem 27 is an operating arm 31 which operating arm is adapted to be actuated by the throttle operating lever. This operation will be hereinafter described.

Secured to the outer end of valve stem 28 is likewise an operating arm 32 which, however, is intended to be manually operated. The purpose and operation of this arm also will shortly be described.

Diametrically opposite the pipe connections 16 and 17 are steam ports 33 and 34 and connecting these ports is a steam passage 35. The bridges 25 and 26 of the valves 20 and 21 are of such width that they effectively close the ports 33 and 34 against the passage of steam when positioned over the same. With the valves 20 and 21 open steam from the pipe 7 will thus pass suc-

cessively through the valve chamber 18, the port 33, the passage 35, the port 34 and the valve chamber 19 into the pipe 9. Also, it will be seen that the valves 20 and 21 are in series with each other respecting the flow of the steam, hence the valve 20 may be termed a primary valve and the valve 21 a secondary valve.

The axis of the secondary valve 21 is a continuation of the axis of the primary valve 20, and these valves have, under certain later described conditions, engagement with each other by means of the concentrically disposed slot 36 in the end of the primary valve 20 and the fixed pin 37 in the adjacent end of the secondary valve 21, the slot being adapted to accommodate the said pin.

The operation of this portion of my invention is as follows: The throttle operating lever being in closed position and the locomotive at rest, the primary valve arm 31, which is operatively connected to the throttle operating lever by means of the link 38 will be in the position shown in Fig. 6. This arm 31 is so positioned on the valve stem 27 that the bridge 25 of the primary valve 20 will leave the steam port 33 uncovered when the valve arm 31 is in the position shown in Fig. 6. Hence steam from the pipe 7 will fill up the valve chamber 18 and the passage 35. At the same time the arm 32 should be standing in the position shown for it in Fig. 6. This valve arm 32 is so positioned on the valve stem 28 that the bridge 26 of the secondary valve 21 will cover the steam port 34 when the valve arm 32 is in this position. Hence the steam now in the passage 35 can not enter the valve chamber 19 or the pipe 9. The relation of the bridges 25 and 26 to the ports 33 and 34 when the valves are in these positions is also shown in Fig. 6. This figure shows also the position of the pin 37 in the slot 36 where it will be seen that the said pin is at the rear end of the slot and that any rotation of the primary valve 20 in the direction of the arrow A will rotate the secondary valve 21 a similar amount. When the throttle operating lever is now moved to the open position, the primary valve 20 will be rotated to the position shown in Fig. 7 and by means of the aforesaid slot 36 and pin 37 the secondary valve 21 will likewise be moved to the position shown for it in Fig. 7, which figure shows the relation of the bridges 25 and 26 to the ports 33 and 34. It will be seen that with the valves in these positions the port 33 is closed and the port 34 open, hence steam from the pipe 7 can now come no farther than into the valve chamber 18. Also the pin 37 is still at the rear end of the slot 36 so that any rotation of the primary valve 20 in the direction of the arrow B will not

produce movement of the secondary valve 21. If the throttle operating lever be now moved to the closed position the primary valve 20 will be rotated to the position shown in Fig. 8, in which position the bridge 25 has uncovered the port 33. The secondary valve 21, however, remains in the same position as in Fig. 7 hence the port 34 remains open. Consequently, steam from the pipe 7 can now flow through the control valve 8 and into the pipe 9 which delivers it to the locomotive cylinders or under some later described conditions to the exhaust pipe. Fig. 8 thus shows the positions of the parts of the control valve 8 when the locomotive is drifting and steam is being supplied to the cylinders for the purposes herein-before stated. The pin 37 is now at the front end of the slot 36 so that the secondary valve 21 may be rotated by means of the arm 32 in the direction of the arrow C without moving the primary valve 20. Hence when the locomotive is stopped and the drifting steam is no longer needed the engineer moves the secondary valve 21 in the direction of the arrow C by means of the arm 32, bringing this valve into the position shown in Fig. 6 and cutting off steam from the pipe 9. All the parts of the control valve 8 now stand in their former positions as in Fig. 6 and the entire mechanism is ready for another cycle of operations. With the throttle operating lever closed and the parts of the control valve in the positions shown in Fig. 8 steam might be delivered directly to the locomotive cylinders through the pipe 9. But when the locomotive is stopped the engineer might forget to close the valve 21 and the live steam passing to the cylinders might cause the locomotive to creep away.

To guard against this possibility, I provide in this auxiliary steam line the by-pass valve 10 which is adapted to permit the flow of steam to the locomotive cylinders until pressure builds up in them and then to bypass the steam to some outlet, such as to the exhaust pipe as shown in the drawings.

To perform these functions this by-pass valve is preferably made as follows, references being to Figs. 9 and 10 of the drawings.

39 is the by-pass valve body having an opening 40 for the connection of the steam supply, which steam is admitted into a chamber 41. Immediately above and below this chamber are pierced walls 42 and 43 these walls being provided with oppositely disposed valve seats 44 and 45.

Above the wall 42 is a chamber 46 and below the wall 43 is a chamber 47, these chambers being provided respectively with pipe outlets 48 and 49 through the body of the by-pass valve.

Extending through the chambers 41, 46

and 47 is a valve spindle 50 having affixed thereto oppositely disposed valves 51 and 52 which are adapted to occupy the seats 44 and 45 respectively. The valves 51 and 52 are spaced farther apart on the spindle 70 than the distance between the valve seats 44 and 45, consequently when one of these valves is seated the other is open, the steam in the chamber 41 thus being shut off from one of the chambers 46 and 47 while being 75 admitted to the other of these chambers.

The upper portion 46^a of the chamber 46 is made cylindrical in cross section so as to accommodate a piston 53. This piston 53 is secured to the valve spindle 50 and is provided with water rings 54 and pressure equalizing holes 58. The chamber 46^a and the piston 53 thus act as a dash pot to cushion the seating of the valves 51 and 52, the holes 58, by equalizing the pressure 85 on both sides of the piston, providing against the area of the piston acting to help or hinder the seating or unseating of the valves 51 and 52. For convenience in manufacturing and assembling, the body of this 90 by-pass valve is provided with removable heads 65 and 66. Also, the valve 52 and the lower portion of the valve spindle 50 are made separate from the valve 51 and the upper portion of the valve spindle, so that 95 these parts may be readily assembled, the bolt 67 holding them together as an integral part. In operation this by-pass valve is connected at 40 to the steam pipe 9 so that the chamber 41 is filled with steam at all 100 times when the control valve 8 is open as already explained.

The steam pipe 11, which is connected to the chamber 47 at 49, is branched at 55, the branch 11^a leading to one of the locomotive 105 cylinder steam pipes, being connected thereto at 56, and the branch 11^b of this pipe being similarly connected to the other cylinder steam pipe, this connection not being shown in the drawings.

From the chamber 46 a pipe 12 leads to the locomotive exhaust pipe 13, this pipe being connected to said exhaust pipe at 57, and to the body of the by-pass valve at 48.

When the locomotive is working, with the 115 throttle valve open and the cylinder steam pipes filled with high pressure steam the valve 52 will be held up against its seat by this steam pressure, the valve 51 consequently being unseated as shown in Fig. 10, 120 and the pipe 9 being in full communication with the pipe 12 and the exhaust pipe 13. With the throttle so opened, however, no steam is passing into the pipe 9 through the control valve 8, although it will be shortly 125 shown how another supply of steam might at this time be passing through the by-pass valve 10.

When the throttle is closed to allow the locomotive to drift the pressure immediately 13

falls off in the cylinder steam pipes 6 and consequently in the chamber 47 so that the valves 51 and 52 drop, the valve 51 seating and the valve 52 opening as shown in Fig. 9, the drifting steam thus being admitted to the cylinder steam pipes and the cylinders through the pipes 11, 11^a and 11^b.

In the event that the locomotive is now brought to a stop and the engineer fails to manually close the control valve 8 the steam pressure immediately begins to build up in the cylinder steam pipes and consequently in the chambers 41 and 47. As soon, however, as this accumulated pressure reaches a predetermined amount the valve 51 is unseated and the valve 52 is seated, thereby by-passing the drifting steam into the exhaust pipe through the pipe 12. The use of this valve 10, therefore, precludes any possibility of the locomotive creeping. At the same time the directing of this column of steam up the stack when the locomotive is standing calls attention to the fact that the control valve has not been closed.

The pipe 12 is connected to the exhaust pipe at 57 because of convenience, but it will be understood that this steam might be otherwise disposed of by any means that would convey it to the atmosphere. Also the point of connection of the pipes 11^a and 11^b to the cylinder steam pipes is not material. Those skilled in the art will understand that when the cylinder steam pipes contain pressure there is present at the same time pressure in some part of the cylinders, either at the front or back of the pistons. Conversely, when the cylinder contains pressure there is present also pressure in the cylinder steam pipes, hence the connection 56 is made to the cylinder steam pipes as at a point where the drifting steam will flow to the cylinders and where pressure influencing the cylinders will close the valve 52. The details of the by-pass valve might also be arranged in other ways to produce the same results by means of pressure from the cylinders.

In some instances it may be desired to use the air pump exhaust as drifting steam. In Fig. 1 I have shown how this may be connected up with the other elements of my invention. Referring to this figure, 59 and 60 are air pumps having exhaust pipes 61 and 62. These pipes 61 and 62 lead to a single exhaust pipe 63 which conveys this air pump exhaust into the steam pipe 9, connection being made therewith intermediate the control valve 8 and the by-pass valve 10 at 64. From this connection the exhaust from the air pump is controlled in the by-pass valve the same as live steam from the control valve, with the exception that when the locomotive is working and the valve 52 is seated and the valve 51 unseated the air pump exhaust will flow unhindered through

the chambers 41 and 46 and thence out through the exhaust pipes 12 and 13.

Thus it will be seen that my invention fully performs all the functions desired. It will also be evident that those skilled in the art might make various changes in the details of this device within the scope of the claims without departing from the spirit thereof.

Having thus described my invention, what I claim is:

1. In a drifting attachment for locomotives the combination with the boiler cylinders, steam pipes, throttle valve and throttle operating lever of an auxiliary steam line adapted to convey steam to said cylinders around said throttle valve, a control valve in said auxiliary steam line, operative means from said throttle operating lever whereby the said control valve is closed when the said throttle valve is opened and opened when the said throttle valve is closed and independent operative means whereby the said control valve may be manually closed after the said throttle valve has been closed, said control valve being so constructed that after being manually closed the next opening of the throttle valve by the said throttle operating lever will move the parts of the said control valve to their normal positions for the opening position of the throttle operating lever.

2. In a drifting attachment for locomotives, the combination with the boiler, cylinders, steam pipes, throttle valve and throttle operating lever of an auxiliary steam pipe adapted to convey steam to said cylinders around said throttle valve, a control valve in said auxiliary steam pipe, operative means from said throttle operating lever whereby the said control valve is opened when the said throttle valve is closed, and a by-pass valve in said auxiliary steam pipe adapted to admit steam to the cylinders when the said cylinders are not under pressure and adapted to shut off steam from the cylinders when the said cylinders are under pressure.

3. In a drifting attachment for locomotives the combination with the boiler, cylinders, steam pipes, throttle valve and throttle operating lever of an auxiliary steam line adapted to convey steam to the cylinders around said throttle valve, a control valve in said auxiliary steam line, operative means from said throttle operating lever whereby the said control valve is closed when the said throttle valve is opened and opened when the said throttle valve is closed, independent operative means whereby the said control valve may be manually closed after the said throttle valve has been closed, and a by-pass valve in said auxiliary steam line adapted to admit steam to the cylinders when the said cylinders are not under pressure.

sure and adapted to shut off steam from the cylinders when said cylinders are under pressure.

4. In a drifting attachment for locomotives the combination with the boiler, cylinders, steam pipes, throttle valve and throttle operating lever of an auxiliary steam line adapted to convey steam to the cylinders around said throttle valve, a control valve in said auxiliary steam line, operative means from said throttle operating lever whereby the said control valve is closed when the said throttle valve is opened and opened when the said throttle valve is closed, independent operative means whereby the said control valve may be manually closed after the said throttle valve has been closed, and a by-pass valve in said auxiliary steam line, and a by-pass pipe from said by-pass valve to the atmosphere, said by-pass valve being adapted to admit steam from said auxiliary steam line to the cylinders when the said cylinders are not under pressure and being further adapted to by-pass the same to the atmosphere when the said cylinders are under pressure.

5. In a drifting attachment for locomotives the combination with the boiler, cylinders, steam pipes, throttle valve, throttle operating lever and air pumps of an auxiliary steam line adapted to convey steam to the cylinders around said throttle valve, a control valve in said auxiliary steam line, operative means from said throttle lever whereby the said control valve is closed when the said throttle valve is opened and opened when the said throttle valve is closed, independent operative means whereby the said control valve may be manually closed after the said throttle valve has been closed, a by-pass valve in said auxiliary steam line, and a by-pass pipe therefrom, said by-pass valve and by-pass pipe being adapted to by-pass steam around the cylinders when said cylinders contain high pressure steam, and a connection to said auxiliary steam line intermediate the said control valve and the said by-pass valve for the admission of the air pump exhaust.

50 6. In a drifting attachment for locomo-

tives the combination with the boiler, cylinders, steam pipes, throttle valve and throttle operating lever of an auxiliary steam line adapted to convey steam to said cylinders and around said throttle valve and a control valve in said auxiliary steam line, said control valve having a primary valve operatively connected to said throttle operating lever and adapted to be opened thereby when the throttle is closed and closed thereby when the throttle is opened and having a secondary valve disposed in series with said primary valve and operatively connected therewith to be opened when said primary valve is closed and to remain open when said primary valve is opened, and independent operating means whereby the said secondary valve may be manually closed when the said primary valve is open.

7. In a drifting attachment for locomotives a source of steam, cylinders, a steam line from said source of steam to said cylinders, a by-pass valve in said steam line and a by-pass pipe from said by-pass valve to the atmosphere, said by-pass valve being adapted to admit steam to the cylinders when the said cylinders are not under pressure and being further adapted to by-pass the steam to the atmosphere when the said cylinders are under pressure.

8. In a drifting arrangement for locomotives the combination with the cylinders and air pumps, of a steam line adapted to convey the exhaust steam from said air pumps to the said cylinders, a by-pass valve in said steam line and a by-pass pipe from said by-pass valve to the atmosphere, said by-pass valve being adapted to admit the said exhaust steam to the cylinders when the said cylinders are not under pressure and being further adapted to by-pass the said exhaust steam to the atmosphere when the said cylinders are under pressure.

In testimony whereof I affix my signature in presence of two witnesses.

JOHN A. PILCHER.
